C. F. JOHNSON

CARBURETOR

Filed Dec. 21, 1916

UNITED STATES PATENT OFFICE.

CHESTER F. JOHNSON, OF DETROIT, MICHIGAN.

CARBURETOR.

Application filed December 21, 1916. Serial No. 138,145.

To all whom it may concern:

Be it known that I, CHESTER F. JOHNSON, a citizen of the United States, and resident of Detroit, Wayne County, State of Michigan, have invented certain new and useful improvements in Carburetors, of which the following is a specification.

This invention relates to carburetors, or fuel mixing devices.

10 One of the objects of this invention is to provide simple, improved, and efficient quality regulators for fuel mixing devices.

Another object of my invention is to provide a carburetor, with improved means for 15 regulating the flow of fuel to the mixing chamber under pre-determined conditions.

In the form illustrated, the various objects are obtained by varying the pressure of the air on the liquid within the fuel 20 chamber.

25 In general, my invention involves the use of a carburetor comprising a mixing chamber, a fuel chamber, therefor, and a nozzle through which fuel from said fuel chamber is discharged into said mixing chamber; and includes means for admitting pressure to the surface of the fuel within the chamber in which it is contained to thereby increase the pressure on the fuel as a throttle valve 30 for controlling the flow of combustible mixture to the engine is opened; thus increasing the richness of the mixture and accelerating the motor with which the carburetor is connected; said throttle valve and said means

35 for admitting pressure to the fuel in the fuel chamber being connected together so as to operate in unison. This means is so arranged that after the throttle is opened wider and has come to rest in a new position 40 the pressure upon the fuel is automatically reduced, whereby a satisfactory mixture for each particular position of the throttle will be secured.

The various objects, purposes, constructions and principles involved, will more 45 clearly appear from the following description, taken in connection with the accompanying drawings, which form a part of this specification, and in which:

50 Figure I is a side elevation with portions broken away, of a carburetor embodying a preferred form of my invention;

Figure II is a vertical section, substantially on the line 2-2 of Figure I; and

55 Figure III is a fragmentary vertical sec-

tion illustrating the air passage connecting the fuel chamber with the mixing chamber.

Referring to the drawings, 10 is the carburetor body comprising a mixing chamber 11, and if desired, the carburetor body may 60 be provided with a laterally extending portion 12, having a port 13 adapted to be controlled by an auxiliary air valve member 14, which is suitably pivoted as at 15, and adapted to be yieldingly closed by a spring 65 16.

The usual butterfly throttle valve 17, may be pivotally mounted at the top of the mixing chamber on a shaft 18, on the end of which may be secured an operating arm 19. 70

Arranged below and suitably secured to the carburetor body 10, is a fuel chamber 20. The fuel chamber comprises a float bowl or shell 21, a cover member 22 having an intake port 23, adapted to be controlled by 75 a needle valve member 24, and a float 25, suitably pivoted to the cover member as at 26. It will be noted that the cover member 22 is formed with a depression 27, in the center of which is formed a fuel nozzle 28, adapted to be fed from the interior of the chamber 20. Suitably mounted between the carburetor body 10 and the cover member 22, is a plate 29 provided with a Venturi tube 30. The fuel chamber 20 is provided 80 with a vent or relatively small air port 31, arranged above the normal level of fuel therein.

It will also be noted that the carburetor is provided with a primary air port 32, 90 formed in the cover member 22, and that the auxiliary air port 13, if any, is in direct communication with the mixing chamber 11, by means of the laterally extending portion 12 of the carburetor body. 95

A conduit, or air passage 33, is provided, connecting the fuel chamber and the mixing chamber by means of the ports 34 and 35 respectively. It will be noted that the vacuum within the mixing chamber 11, will 100 be communicated to the fuel chamber 20, thus tending to normally reduce the effect of atmospheric pressure on the fuel within the chamber, and thereby retarding the flow of fuel 105 through the nozzle 28.

The previously described parts and passages of the carburetor, are so proportioned and adjusted, that with the throttle in any fixed position, such as for "idling" or "la- 110

boring" of the motor, or high speed light running conditions, the mixture produced is adequate and sufficient for such conditions.

While the previously described construction and arrangement of parts may be sufficient for fixed running conditions, it is desired to produce, at times, a richer mixture such as when the throttle valve 17 is opened quickly for accelerating the motor. This 10 means may be in the form of a relatively large air vent or port 36, formed in the cover member 22, of the fuel chamber 20. This port may be controlled by a valve member 37, having a piston or plunger portion 38 arranged in a cylindrical member 39, having a pivotal connection as at 40, with an arm 41, fixed to the throttle shaft 18. The plunger portion 38 of the valve member 37, is so dimensioned that it fits rather closely in the 20 cylinder 39.

It will be noted that with the throttle in closed position, the valve member 37 will rest on, and render the port 36 inactive. If the throttle valve 17 is opened quickly, it 25 will simultaneously lift the cylinder 39, and any tendency for the valve member 37 to remain in its closed position will be momentarily overcome by the suction between the top of the piston 38 and the cylinder 39, 30 thus opening the port 36 and decreasing the tendency of the air passage 33 to retard the flow of fuel through the nozzle 28, and thereby accelerating the flow of fuel therefrom.

35 A spring 42, may be arranged between the end of the piston portion 38 and the cylinder 39, for gradually relieving the vacuum within the cylinder and returning the valve member 37 to its seat. The return movement 40 of the valve member 37 to its seat will, of course, be governed by the amount of clearance provided between the piston portion and the cylinder 39. If the clearance is great enough, there will, of course, be no necessity for the spring 42, as gravity will return the valve member 37 to its seat. This clearance may be made variable by having the 45 piston and cylinder formed of metals having different coefficients of expansion, thus 50 automatically compensating for variations of climatic or temperature conditions.

It will be understood from the foregoing description, that the port 36 is normally closed by its valve, regardless of the throttle 55 position, thereby producing a certain quality of mixture, but should it be desired to accelerate the motor by throwing the throttle 17 open wider, the valve 37 would be lifted by the throttle arm 41, and the cylinder 39, 60 after which the valve is slowly returned to its seat, and, of course, the flow of fuel through the nozzle 28 will be accelerated during the period the port 36 is open, with the result that the mixture is enriched for providing an accelerating mixture.

While I have described and will specifically claim what I deem to be a preferred embodiment of my invention, it will be obvious to those skilled in the art, that various modifications and changes may be made 70 without departing from the spirit and scope thereof.

Having thus described my invention, what I claim and desire to secure by Letters Patent is:

1. In a carburetor for internal combustion engines, a fuel chamber, a mixing chamber, a fuel passage leading from the fuel chamber to the mixing chamber, a throttle valve, and means independent of the suction of the engine and yieldingly connected with said throttle valve for admitting pressure to the surface of the fuel in said chamber whereby the flow of fuel through said passage is controlled. 80

2. In a carburetor, a fuel chamber having an air port leading thereto, a valve controlling said port, a mixing chamber, a fuel passage leading from the fuel chamber to the mixing chamber, a throttle valve, and means comprising an extensible connection for operating said first valve with said throttle valve. 90

3. In a carburetor, a first passage through which air flows on its way to the engine, a fuel chamber arranged to supply fuel to said passage, a second passage leading from a point in the fuel chamber above the level of fuel therein to said first passage and tending to establish sub-atmospheric pressure in said chamber, a throttle valve for the first passage, and means for momentarily increasing and afterwards reducing the pressure in the fuel chamber when the throttle valve is moved in one direction. 95

4. In a carburetor comprising a fuel chamber, a mixing chamber connected therewith, and a throttle valve for controlling the flow of fluid through the mixing chamber, an air port leading to said fuel chamber above the level of the fuel therein, a valve for said port, and means connecting said two valves so constructed and arranged that the second mentioned valve is opened as the throttle valve is moved quickly in one direction, and is thereafter automatically gradually closed independently of the throttle valve. 100

5. In a carburetor, the combination with a fuel chamber having an air port, a valve for said port, a mixture passage supplied with fuel from said chamber, a throttle valve for said passage, and interconnected means, independent of the suction of an engine to which the carburetor may be connected, for simultaneously opening said valves, said means permitting the closing of said first valve independently of said second valve. 110

6. In a carburetor, a passage through which air flows to an engine, a fuel chamber 120

communicating therewith, a port for admitting air to the fuel chamber, a passage connecting the first named passage to the fuel chamber above the level of the fuel therein, 5 and means acting to normally close the port, said means including a cylinder and piston construction arranged to open the port at will and to thereafter gradually close said port.

10 7. In a carburetor, a passage through which air flows to the engine, a fuel chamber communicating therewith, a port for

admitting air to said chamber, a passage connecting said first named passage to the upper part of said chamber to reduce the 15 pressure therein when the engine is running, a valve for said port, a throttle for the first named passage, and a temperature responsive connection between said throttle and said valve.

In testimony whereof I affix my signature.

CHESTER F. JOHNSON.
